[57] CLAIM

The ornamental design for a teleprinter keyboard and telephone, substantially as shown and described.

DESCRIPTION

FIG. 1 is a front, top and left side perspective view of a teleprinter keyboard and telephone showing our new design;

FIG. 2 is a left side elevational view thereof;

FIG. 3 is a right side elevational view thereof; and
FIG. 4 is a rear elevational view thereof taken along
lines 4-4 of FIG. 3.

FIG. 4
